UNITED STATES PATENT OFFICE.

GEORGE D. EIGHMIE, OF NEW YORK, N. Y.

GAS-ENGINE.

1,234,314.

Specification of Letters Patent. Patented July 24, 1917.

Application filed August 26, 1915. Serial No. 47,412.

To all whom it may concern:

Be it known that I, GEORGE D. EIGHMIE, a citizen of the United States, residing at New York, in the county of New York and 5 State of New York, have invented certain new and useful Improvements in Gas-Engines, of which the following is a specification, reference being had therein to the accompanying drawing.

10 My present invention relates particularly to two-cycle gas engines and has for its object the prompter and more complete disposal of the burnt gases after each explosion, as well as the more effectual introduction 15 of the explosive charge into the working chamber. To these ends the most important feature of the invention consists in the novel arrangement of the ports through 20 which the gaseous charge is introduced into the explosion chamber in the interior of the cylinder; and also the invention consists in numerous details and peculiarities in the construction, arrangement and combination 25 of the various parts, substantially as will be hereinafter described and then more particularly pointed out in the appended claims.

In the accompanying drawing illustrating my invention:

Figure 1 is a vertical section of my improved gas engine;

Fig. 2 is a cross-section on the line 2, 2 of Fig. 1;

Fig. 3 is an enlarged vertical section showing the arrangement of the ports for delivering the mixture from the interior of the piston into the cylinder, the parts being in the position that they occupy just prior to the opening of the ports but while they are still closed.

40 Fig. 4 is a similar vertical section showing the same parts in the position that they occupy when the ports are open.

Similar characters of reference designate corresponding parts throughout the different figures of the drawing.

1 denotes the cylinder or working chamber of the engine which may be of any desired length and diameter, and which extends downwardly and is supported on the 50 crank casing 2, through which extends the crank shaft 3, having thereon a crank 4, provided with crank pin 5, to which is attached the connecting rod 6 which is fastened to the working piston 7, which latter is shown as of the trunk type of piston.

The lower portion of the cylinder 1, just

above the crank case 2, is surrounded by the annular supply port 8 which receives the explosive mixture at some suitable point, as for instance, the inlet opening 9, and delivers the same into the interior of cylinder 1 at the opening 10 of said annular port 8, said opening 10 being of circular form and extending entirely around the cylinder so that a large charge may be quickly introduced into the cylinder, the same being conducive to a high speed operation of the engine. The cylinder 1 is also provided at a short distance from the annular port 10 with an exhaust port 11, which also extends 70 completely around the same, so as to provide a large port area. When the trunk piston 7 moves upwardly sufficiently far to open the port 10, a charge of the explosive mixture will obviously be introduced into 75 the interior of the piston 7, and when, on its reverse stroke, it drops below the exhaust port 11, this exhaust port 11 will be opened so as to allow of the exit of the spent products of the explosion. Thus it will be 80 seen that the piston 7 in its top position overruns the inlet port and in its bottom position overruns the exhaust port.

The piston 7 is provided with an upwardly-extending tubular extension 12 85 which communicates with the hollow interior of the piston. This tubular projection 12 fits snugly in a dome 13 mounted upon the cylinder head 14. Dome 13 and piston extension 12 have a sliding fit and 90 form a gas tight and air tight joint between them. Within the dome 13 is a plug 15, securely held therein and providing an annular space between it and the dome 13 which is used to guide the tubular piston extension 95 12 during its reciprocations. Said plug 15 is held in position by any suitable means. On the lower end of the plug 15 and below its bottom 16 is a tubular extension 17 which enters the piston extension 12 with a sliding 100 fit forming a gas tight joint and telescopes neatly with said piston extension so that the latter during its reciprocations may slide easily up and down over this tubular projection 17, as also between it and the dome 13, and between the plug 15 and the dome 13, all as clearly shown in the figures of the drawing.

The tubular extension 12 of the piston is provided near its upper end with an encircling port 18 extending completely around it with the exception of a few ribs,

needed to keep the tube intact, and through this port 18 the explosive mixture is discharged in part from the interior of the piston into the explosion chamber when the 5 port is open, a discharge being also made past the end of the tube 12 when the latter drops below the cylinder head 14. The plug extension 17 is provided at a short distance from its lower end with a port 19 10 extending completely around it, except for two or three ribs needed to keep the tubular part 17 intact with the plug 16, and as this tubular part 17 communicates with the interior of the piston extension 12, it will 15 be obvious that the gaseous contents of the piston will emerge through the port 19 when the upper end of the tube 12 drops below said port 19, and will then pass into the working chamber of the cylinder 1 between the end of the tube 12 and the cylinder head 14 when said tube 12 drops below the head 14. By referring to Figs. 1 and 3, it will 20 be observed that the tubular part 12 of the piston is on its down stroke and is at a point where the upper end of the tube 12 is about to be released from the cylinder head 14 and the port 18 is about to drop below the lower end of the part 17, it being noted that the said lower end of the tube 25 17 is provided with a plurality of fingers or projections 20, which engage the interior of the tube 12 so that the lower end of the part 17 is kept in engagement with the tube 12 when the port 18 is open, said 30 projections 20 in effect providing a port between them which coincides with the port 18 when the tube 12 drops far enough down; therefore, when the tube 12 drops below the piston head 14, the gaseous contents of 35 the piston will not only pass through the port 19 and through the gap between the end of tube 12 and the cylinder head 14, but will also pass between the projections 20 and through the port 18 likewise into the working 40 chamber of the cylinder. I have moreover found it of considerable advantage to provide the outer wall of the tubular extension 17 which fits against the inside surface of the tube 12 with a horizontal encircling 45 groove 21, which forms a port through which, when the piston is on its downward stroke, a part of the explosive mixture will be introduced from the interior of the piston into the working chamber. This port 21 50 opens simultaneously with the opening of the other ports, all as shown in Fig. 4 where all these ports are seen to be open and allowing the explosive mixture to pass from the interior of the tube 12 into the working 55 chamber of the cylinder. In Figs. 1 and 60 3, all three ports are shown as closed.

In view of the foregoing description, the 65 operation of my improved gas engine will be readily understood without any additional detailed explanation with reference

to such operation. In the wall of the cylinder 1 is a spark plug 22 or some equivalent device for igniting the mixture. This mixture of air and gas is supplied to the engine at the inlet 9 through the annular port 70 8 and the inlet port 10, and thence into the interior of the piston 7 when the latter is at the upper end of its stroke and its tubular extension 12 is within the dome 13 and is occupying the annular space between the 75 dome 13 and the plug 15, at which time obviously the exhaust port 11 is closed and also the transfer ports for delivering the explosive mixture from the interior of the piston into the working chamber. When the 80 explosion takes place and the previously compressed charge drives the piston to the lowest limit of its stroke, covering the annular port 10 and opening the exhaust port 11, the charge which has just been exploded 85 will escape through said port 11, and the fresh mixture which was introduced through the port 10 into the cylinder and which fills the interior of the piston, will, as soon as the piston drops so that the telescoping parts 90 17 and 12 will open the transfer ports 18, 19 and 21, be carried into the working chamber of the cylinder, which will be filled above the piston with the new charge, the entrance of the new charge assisting in the 95 expulsion of the spent products through the exhaust port 11. As soon as this new charge is introduced, the piston will begin its upward movement on the next cycle and will 100 compress the charge so introduced, at the same time closing the transfer ports and the same cycle of operations will proceed as before.

Having thus described my invention, what I claim as new and desire to secure by Letters Patent, is:

1. In a two-cycle gas engine, the combination with a cylinder and its head, of a central tubular extension on said cylinder head, a hollow piston working within said cylinder and having a tubular extension which enters a tubular extension on the cylinder head and is provided with a port near the end thereof, through which port the explosive mixture is discharged from the interior 110 of the piston into the explosion chamber when said port is open, a discharge being also made past the end of said piston extension when it drops below the cylinder head, and a plug located within the cylinder head 115 extension so as to leave an annular space between it and the wall of said extension, said plug on its lower end having a tubular part with a port, said tubular part entering the tubular extension of the piston and covering 120 and uncovering the port therein, and said port in the tubular part on the plug discharging the gaseous contents of the piston when the upper end of the piston tube drops 125 below the same, all of said ports and parts 130

being thus arranged with the cylinder to operate a plurality of openings simultaneously.

2. In a two-cycle gas engine, the combination with a cylinder and its head, of a hollow piston working within said cylinder, said piston having a tubular extension provided with a port through which the explosive mixture is discharged from the interior 10 of the piston into the explosion chamber when the port is open, a discharge being also made past the end of said piston extension when it drops below the cylinder head, a guide device on the end of the cylinder consisting of two members between which is an 15 annular guideway which receives the aforesaid ported piston tube, and a tubular part carried by the guide device and provided with a port and engaging the tubular ex- 20 tension on the piston, said port in said tubular part discharging the gaseous contents of the piston when the upper end of the piston tube drops below said port, all the ports and parts being arranged with the cylinder head 25 to operate a plurality of openings simultaneously.

3. In a two-cycle gas engine, the combination of a cylinder having inlet and exhaust ports, a hollow trunk piston working in said cylinder and having a tubular extension provided with a port near its end, an annular guide in the cylinder head consisting of a tubular extension on said head and a plug supported in said extension and having a 30 closed end, and a tube attached to said plug and provided with a port in its wall and also a grooved by-pass or port, said tubular extension being embraced by the piston extension in its reciprocatory movement.

4. In a two-cycle gas engine, the combination with a cylinder having inlet and exhaust ports and a concentric tubular extension on the head thereof, of a piston working within said cylinder and covering and

uncovering the inlet and exhaust ports during its reciprocatory movement, said piston having a tubular extension which enters the tubular extension on the cylinder and is provided with a port near the end thereof, a plug located within the cylinder extension 45 so as to leave an annular guideway for the piston extension, said plug carrying a tubular part having a port in its wall and also a grooved by-pass or port, said tubular part entering the tubular extension of the piston, 50 all of said ports being arranged so as to open when the end of the tubular piston extension withdraws from the annular guideway and disengages itself temporarily from the cylinder head to allow the gaseous mixture to pass from the interior of the piston 55 into the explosion chamber.

5. In a two-cycle gas engine, the combination of a cylinder and its head, a piston working in said cylinder and having a tubular extension provided with a port, through which port the explosive mixture is discharged from the interior of the piston at times, a discharge being also made past the end of said piston tube when it is released 60 from the cylinder head, a tubular extension on the cylinder head, a plug in said extension and concentric therewith so as to leave an annular space that receives and guides the tubular extension of the piston, a tubular 65 part carried by the said plug and entering the piston extension so as to cover and uncover the port therein, said plug tube having a port in its wall through which the explosive mixture from the interior of the piston 70 may at times be transferred to the working chamber of the piston, said ports and parts being arranged with the cylinder head to 75 operate a plurality of openings simultaneously.

In testimony whereof I affix my signature.

GEORGE D. EIGHMIE.
